COMBINED BOX, COVER, AND LIQUID DIFFUSER

Howel H. Hopson, New York, N. Y., assignor of one-half to Alfred Landes, New York, N. Y.

Application February 16, 1953, Serial No. 23,640

Term of patent 3½ years

(Cl. D85—7)

Fig. 1.

Fig. 2.

Fig. 3.

To all whom it may concern:

Be it known that I, Howel H. Hopson, a citizen of the United States, residing at New York, county of New York, and State of New York, have invented a new, original, and ornamental Design for a Combined Box, Cover, and Liquid Diffuser, of which the following is a specification, reference being had to the accompanying drawing, forming a part hereof.

Figure 1 is a front elevation of a combined box, cover, and liquid diffuser, showing my new design.

Figure 2 is an end elevation thereof, and

Figure 3 is a perspective view of the cover portion thereof as viewed from the underside of the cover.

The dominant features of my design reside in the portions shown in full lines. The sides of the combined box, cover and liquid diffuser not shown are the same as those shown.

I claim:

The ornamental design for a combined box, cover, and liquid diffuser, as shown and described.
